UNITED STATES PATENT OFFICE.

CARL OSCAR NORDENSSON, OF SCANE, SWEDEN, ASSIGNOR OF ONE-HALF
TO JOHN A. LAIRD, OF ST. LOUIS, MISSOURI.

MACHINE FOR CLEANING GAS.

No. 820,247.

Specification of Letters Patent.

Patented May 8, 1906.

Application filed September 11, 1905. Serial No. 277,853.

To all whom it may concern:

Be it known that I, CARL OSCAR NORDENSSON, a subject of the King of Sweden and Norway, and a resident of Scane, Sweden, 5 have invented a new and useful Machine for Cleaning Gas, of which the following is a specification.

My invention relates to a machine for extracting tar and solid matter from gas; and it 10 consists in the combinations and arrangements of parts hereinafter described and claimed.

In the accompanying drawings, which 15 form part of this specification, and wherein like symbols refer to like parts wherever they occur, Figure 1 is a vertical longitudinal section of my machine, and Fig. 2 is a vertical cross-section thereof.

My machine comprises a hollow shaft 1, 20 preferably horizontal, mounted in suitable journal-bearings on a main frame 2. Affixed to this hollow shaft are a number of radial vanes 3, arranged longitudinally of the shaft or with a helical twist. Preferably 25 these vanes have perforations 4 therein, which perforations are more efficient at the outer marginal portion of the vane. Mounted in the framework 2 concentrically with the hollow shaft is a cylindrical casing 5, 30 which incloses said shaft and the vanes thereon. Mounted inside of this casing is a perforated shell 6 closely adjacent to the outer margins of the vanes. Preferably this shell is of conical form tapering from the inlet end 35 to the outlet end, and the vanes likewise taper to conform to the shell. By this arrangement the annular space surrounding the perforated shell increases in width from the inlet end toward the outlet end.

40 The hollow shaft 1 is closed at one end and at the other end is connected by a pipe 7, controlled by a valve 8, to any suitable source of water-supply. The portion of the shaft within the casing has radial perforations 9, 45 whereby the water from the source of supply may pass into the interior of the perforated shell 6. These perforations are designed to deliver small streams of water, but should not be so small as to be liable to be clogged by the 50 deposit of tar thereon. At its lowermost portion the casing 5 is provided with a pipe 10 for the outflow of water, and this outlet pipe 10 leads into a tank or well 11. The casing 5 has end plates 12 thereon, which are

provided with central openings 13, communicating with chambers 14 15 in the framework. One of these last-mentioned chambers 14 is connected to a gas-producer, and the other chamber 15 communicates with a gas tank or holder. The shaft 1 is provided 55 with any suitable means for driving it—as, for instance, with a pulley 16, adapted to be driven by a belt from any suitable source of power.

The operation of my device is as follows: 60 The shaft 1 is set in motion and the valve 8 is opened. Thereupon water runs from the source of supply through the pipe 7 and the hollow shaft 1, from the perforations in which it issues in small streams into the interior of 65 the perforated shell 6. The water thus delivered inside of the perforated shell runs through the perforations therein into the space surrounding said shell and thence issues through the outlet-pipe 10 into the well 70 11. The gas from the producer passes through the chamber 14 directly into the interior of the perforated casing 6, and thence passes through the openings in said casing 75 into the space surrounding said casing, and 80 thence into the chamber 15 at the opposite end of the framework, and thence into the gas tank or holder. The small streams of water issuing from the shaft effect an initial 85 distribution of the water with some degree of uniformity throughout the perforated shell and the gas therein, and the vanes of the rapidly-rotating shaft act as beaters to break the water into spray and effect the thorough 90 commingling of the water and the gas. This function of the beaters is increased by the 95 perforations therein. The effectiveness of the beaters depends upon the density of the gas in the casing and the velocity of the beaters. By giving the vanes a helical twist 100 the density of the gas may be increased, and by increasing the width of the vanes at the inlet end the velocity of the marginal portion of the beater at the inlet end is greater than at the outlet end. As the centrifugal action 105 throws the gas toward the circumference and the beating action is principally at the outer portion of the vanes, these arrangements tend to utilize the full length of the casing. In consequence of the space surrounding the 110 perforated casing increasing in width from the inlet end to the outlet end there is also a tendency for the current of gas to be dis-

tributed throughout the full length of the shell. In consequence of these arrangements the particles of tar carried in the gas are cooled and taken up by the water in the form 5 of a mixture which runs out through the outlet-pipe into the delivery-well. In the delivery-well the tar gradually separates from the water and rises to the surface thereof. Either continuously or from time to time the 10 tar is drawn off from the surface of the water in the delivery-well, and the water is drawn off from a point below the level of the tar.

It is noted that the bearings of the hollow shaft are kept cool by the cold water flowing 15 therethrough.

What I claim is—

1. A machine for removing tar and solid matter from gas consisting of a framework, a hollow shaft mounted in said framework and 20 having radial perforations therein and having beater-blades thereon, a casing mounted on said framework and surrounding said beater-blades, a perforated shell inside of said casing, an inlet-pipe connected with said hollow 25 shaft and an outlet-pipe connected with the lower end of said casing, said machine being provided with two passage-ways one of which opens into the interior of said shell and the second of which opens into said casing at 30 a point outside of said shell.

2. A machine for removing tar and solid matter from gas consisting of a framework, a hollow shaft mounted in said framework and having radial perforations therein and having 35 beater-blades thereon, a casing mounted on said framework and surrounding said beater-blades, a perforated shell inside of said casing adjacent to the edges of said blades, an inlet-pipe connected with said hollow shaft 40 and an outlet-pipe connected with the lower end of said casing, said machine having two passage-ways one of which opens into the interior of said shell and the second of which opens into said casing at a point outside of 45 said shell, and said beater-blades being wider at the inlet end than at the outlet end of said casing.

3. A machine for removing tar and solid matter from gas consisting of a framework, a hollow shaft mounted in said framework and having radial perforations therein and having 50 beater-blades thereon, an elongated casing mounted on said framework and sur-

rounding said beater-blades, an elongated perforated conical shell inside of said casing, 55 an inlet-pipe connected with said hollow shaft and an outlet-pipe connected with the lower end of said casing, said machine having two passage-ways one of which opens into the interior of said shell and the second of which 60 opens into said casing at a point outside of said shell, and said beater-blades having their outer margins inclined to conform to the inner surface of the conical shell.

4. A machine for removing tar and solid matter from gas consisting of a framework, a hollow shaft mounted in said framework and having radial perforations therein and having 65 beater-blades thereon, an elongated casing mounted on said framework and surrounding said beater-blades, an elongated perforated conical shell inside of said casing, 70 an inlet-pipe connected with said hollow shaft and an outlet-pipe connected with the lower end of said casing, said machine having two passage-ways one of which opens into the interior of said shell and the second of which 75 opens into said casing at a point outside of said shell, and said beater-blades having their outer margins inclined to conform to the inner surface of the conical shell and having 80 perforations therein.

5. A machine for removing tar and solid matter from gas consisting of a framework, a hollow shaft mounted in said framework and having radial perforations therein and beater-blades thereon, an elongated cylindrical casing mounted on said framework and surrounding said beater-blades, an elongated perforated conical shell inside of said casing, 85 an inlet-pipe connected with said hollow shaft and an outlet-pipe connected with the lower 90 end of said casing, said machine having two passage-ways one of which opens into the interior of said shell and the second of which 95 opens into said casing at a point outside of said shell, and said beater-blades having their outer margins inclined to conform to the inner surface of the conical shell.

Signed at St. Louis, Missouri, September 9, 100
1905.
